E. L. Webster

By *Watson E. Coleman*
Attorney

UNITED STATES PATENT OFFICE.

EDWARD L. WEBSTER, OF WHEATLAND, WYOMING.

ENVELOP.

1,344,071.

Specification of Letters Patent. Patented June 22, 1920.

Application filed March 22, 1919. Serial No. 284,260.

To all whom it may concern:

Be it known that I, EDWARD L. WEBSTER, a citizen of the United States, residing at Wheatland, in the county of Platte and State of Wyoming, have invented certain new and useful Improvements in Envelops, of which the following is a specification, reference being had to the accompanying drawings.

10 This invention relates to certain improvements in envelops, and has relation more particularly to an envelop of a return type, and it is an object of the invention to provide a novel and improved device of this 15 general character whereby the same is readily reversible so that the same may be employed to advantage for two usages, and wherein the same is effectually sealed in each instance.

20 It is also an object of the invention to provide a novel and improved device of this character including a central or body flap provided with side flaps, and wherein said body flap and side flaps are provided with 25 end tabs or flaps coacting with the body and side flaps in a manner to permit a ready reversal of the envelop.

It is also an object of the invention to 30 provide a novel and improved envelop of this general character embodying a body flap and side flaps adapted to be reversibly folded as the occasions of practice may require, and wherein each of the side flaps is provided with means whereby the same may 35 be individually employed as a sealing flap.

The invention consists in the details of 40 construction and in the combination and arrangement of the several parts of my improved envelop whereby certain important advantages are attained and the device rendered simpler, less expensive and otherwise more convenient and advantageous for use, as will be hereinafter more fully set forth.

The novel features of my invention will 45 hereinafter be definitely claimed.

In order that my invention may be the better understood, I will now proceed to describe the same with reference to the accompanying drawings, wherein:

50 Figure 1 is a view in plan of a blank from which my improved envelop is initially formed;

Fig. 2 is a view showing the blank as disclosed in Fig. 1 partially folded;

55 Fig. 3 is a view in plan illustrating the envelop completely folded;

Fig. 4 is a view in plan of the envelop opposite that shown in Fig. 3;

Fig. 5 is an enlarged sectional view taken substantially on the line 5—5 Fig. 2; 60

Fig. 6 is an enlarged sectional view taken substantially on the line 6—6 Fig. 3;

Fig. 7 is a view in plan of the blank reversed after the envelop has been once sealed before being reversed; 65

Fig. 8 is a view in plan showing the envelop as illustrated in Fig. 7 partially folded for a second use;

Fig. 9 is a view in plan illustrating the envelop completely reversed; 70

Fig. 10 is a view in plan of the envelop opposite to that illustrated in Fig. 9;

Fig. 11 is an enlarged sectional view taken substantially on the line 11—11 of Fig. 8;

Fig. 12 is an enlarged sectional view taken 75 substantially on the line 12—12 Fig. 9.

As herein disclosed, my improved envelop comprises a blank consisting of the main flap 1 and the side flaps 2 and 3. Each of the flaps 2 and 3 is of a width in excess 80 of one-half the width of the flap 1.

The flap 1 is provided with the end securing flaps 4 having their opposite end portions 5 and 6 gummed with the gummed surface of the end portion 5 adjacent the side 85 flap 3 and the gummed extremities 6 adjacent the side flap 2. The extremities 5 are preferably square for a purpose which will hereinafter be more fully explained. The side flaps 2 and 3 are provided with the 90 end securing flaps 7 and 8 respectively, and said flaps are each provided with a gummed surface. The gummed faces of the flaps 7 are reverse to the gummed surfaces of the flaps 8, and said gummed surfaces of the 95 flaps 7 and 8 are also reversed relative to the adjacent extremities 5 or 6 of the flaps 4.

The longitudinal marginal portion of the flap 2 and preferably at one side of the longitudinal center thereof is provided with a 100 plurality of notches or recesses *a* affording therebetween a sealing tongue 9 having one face gummed. The gummed face of the tongue 9 is at the same side of the flap 2 as the gummed surfaces of the flaps 7 when 105 my improved envelop is extended or in blank. The outer longitudinal marginal portion of the flap 3, preferably to one side of its longitudinal center, is provided with the spaced notches or recesses *b*, affording 110 therebetween a sealing tongue 10. A face of the tongue 10 is also gummed, and said

gummed face is at the same side of the flap 3 as the gummed surfaces of the flaps 3 when the envelop is extended or in blank.

In first assembling my improved envelop, 5 the flaps 8 are folded inwardly to overlie the end portions of the flap 3, and the flap 3 is then folded to overlie the flap 1. The flaps 4 are then folded over the flaps 3 and 1 and the extremity 5 of the flaps 4 secured to the 10 outer face of the flap 3. After the desired contents have been inserted between the flaps 1 and 3, the flap 2 is folded over the flap 1 and the flap 3 and the end flaps 7 are folded to overlie the outer face of the flap 1 and are 15 secured thereto by the gummed surfaces of said flaps 7. The gummed surface of the tongue 9 is then engaged with the flap 3.

When it is desired to have access within the envelop sealed as just explained, the 20 flaps 7 are separated from the flap 2 and the tongue 9 is also separated from the flap 2 and preferably on the line *c* as indicated in Fig. 3. It is also desired that the extremities 5 of the flaps 4 be separated from 25 said flap 4 by cutting on the line *d* as also indicated in Fig. 3.

In reversing the envelop and with the blank as illustrated in Fig. 7 the flap 2 is first folded to overlie the flap 1, and then 30 the flaps 4 are folded to overlie both the flaps 1 and 2, and the gummed surfaces of the extremity 6 of the flaps 4 are secured to the outer surface of the folded flap 2. To seal the reversed envelop the flap 3 is folded 35 upon the flap 1 and the flap 2 and the flaps 8 are folded to overlie the outer face of the flap 1, or more particularly the severed flap 7. The gummed surface of the tongue 10 is then engaged with the flap 2.

40 From the foregoing description, it is thought to be obvious that an envelop constructed in accordance with my invention is particularly well adapted for use by reason of the convenience and facility with which 45 it may be assembled and operated, and it will also be obvious that my invention is susceptible of some change and modification without departing from the principles and spirit thereof, and for this reason I do not 50 wish to be understood as limiting myself to the precise arrangement and formation of the several parts herein shown in carrying

out my invention in practice except as hereinafter claimed.

What is claimed is:

55 1. A reversible envelop comprising a blank consisting of a body flap, side flaps, end flaps carried by the body flaps and the side flaps, the end flaps of the side flaps having gummed surfaces, the gummed surfaces 60 of the end flaps of one side flap being reverse to the gummed surfaces of the end flaps of the second side flap, the extremities of the end flaps of the body flap also having gummed surfaces, the gummed surfaces 65 at the extremities of each end flap of the body flaps being on reverse sides, the outer longitudinal marginal portions of each of the side flaps being provided with longitudinally spaced recesses affording therebetween 70 a sealing tongue, the surface of each of the sealing tongues being gummed, the gummed surface of one tongue being reverse to the gummed surface of the second tongue.

75 2. A reversible envelop comprising a blank consisting of a body flap, side flaps, end flaps carried by the body flaps and the side flaps, the end flaps of the side flaps having gummed surfaces, the gummed surfaces 80 of the end flaps of one side flap being reverse to the gummed surfaces of the end flaps of the second side flap, the extremities of the end flaps of the body flap also having gummed surfaces, the gummed surfaces 85 at the extremities of each end flap of the body flaps being on reverse sides, the outer longitudinal marginal portions of each of the side flaps being provided with longitudinally spaced recesses affording therebetween 90 a sealing tongue, the surface of each of the sealing tongues being gummed, the gummed surface of one tongue being reverse to the gummed surface of the second tongue, the sealing tongues of the side flaps being at opposite sides of the longitudinal center of 95 the envelop.

In testimony whereof I hereunto affix my signature in the presence of two witnesses.

EDWARD L. WEBSTER.
